CLAIM

The ornamental design for a patio chair, as shown and described.

DESCRIPTION

FIG. 1 is a front perspective view of a patio chair showing the new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right elevation view thereof; and,

FIG. 7 is a left elevation view thereof.

The broken lines in the drawings are for the purpose of illustrating portions of the article that form no part of the claimed design.
